OPERATING MECHANISM OF VEHICULAR TOYS

Masakichi Fujii, Nippori Machi, Arakawa Ku,
Tokyo, JapanApplication December 22, 1936, Serial No. 117,118
In Japan December 27, 1935

3 Claims. (Cl. 46—212)

The present invention relates to an improvement in the operating mechanism of vehicular toys, especially toy motor cars, toy tram cars, toy animals, etc.

5 The primary object of the invention is to provide a mechanical toy of the vehicular type having reversing means operable by contact with the surface over which the vehicle is traveling, and means actuatable by contact with an obstacle 10 in the path of the vehicle for lowering the reversing means into contact with the surface over which the vehicle is moving.

A further object of the invention is to provide a mechanical toy of the character described and 15 having means operable by said obstacle-contacting means to vary the direction of forward movement of the vehicle.

The characteristic feature of this invention may be clearly understood from the following detailed 20 explanation with regard to the accompanying drawing, and it is needless to say that the present invention may have its construction altered variously within the scope of the claims.

Figure 1 is a plan of a toy automobile fitted 25 with the operating mechanism of this invention and having its cover removed;

Figure 2 is a longitudinal section of the same;

Figure 3 is a partial cross section showing the mechanism when moving forward;

30 Figure 4 is a cross section of the same showing the mechanism when moving backward;

Figure 5 is a perspective of a mutilated gear forming part of the invention;

Figure 6 is a perspective of an operating member and slideable member and

Figure 7 is a perspective of a complete toy automobile embodying the present invention.

As shown in the drawing, a frame 2 secured 40 to the base plate 1 of the body is equipped with a spring motor 3 which is wound up by a driving shaft 4. A toothed wheel 5 rotated by the spring motor 3 turns one of the rear wheels, for instance the wheel 9, in the forward direction by means of a pinion 6, toothed wheel 7 and pinion 8, the 45 above wheel 9 being keyed to a shaft 10 mounted in the frame 2 and a supporting arm 13. A toothed wheel 11 fixed to said shaft 10 is engaged with a pinion 12, which is secured fixedly together with the wheel 14 on a shaft in the frame

50 2 and the shaft projects outside said frame 2 and is provided with a pinion 14' keyed to its end, while the other rear wheel 15 is fitted freely on the end portion of a crank shaft 16 separately from the axle of the wheel 9, and a mutilated gear 18 provided with a laterally extending tongue

17 is secured to the above shaft 16 at the outside of the frame 2 (see Figure 5). Said mutilated gear 18 is not engaged with the pinion 14' during the forward movement of the body, the said pinion being normally opposite the toothless portion of the gear 18. On the front base plate of the body is a slideable member 20 having a bumper 19 projecting from its end. The rear end 21 of said member is bent to be engaged with an operating member 22 extending to the outside 10 of the frame through the slots of the guide members 23 and 24 of the frame 2. A pawl 25 at the inside of the above member 22 normally contacts with the projection 17 of the mutilated gear 18. The slideable member 20 and the operating member 22 are held in a fixed position by a helical spring 26 and one of the front wheels, for instance the wheel 27, is maintained out of contact with the floor or other surface on which the car runs, by the inclination of a shaft 28.

20 During forward movement of the vehicle, should its bumper 19 encounter an obstruction, such for instance as a wall, fence or other obstacle, the force of the impact will cause the bumper and thereby the operating member 22 to move 25 backward against the tension of the spring 26, thereby moving the pawl 25 out of engagement with the tongue 17 and leaving the mutilated gear 18 free to rotate with the crank shaft 16 sufficiently to bring the toothed portion of said gear into mesh with the pinion 14'. The crank shaft 16 will thus be rotated so as to raise the wheel 15 relatively to the vehicle body, whereby the latter will assume the inclined position shown in Fig. 4, so that the wheel 14 engages the 30 surface over which the vehicle is moving, thus causing the vehicle to move backward. When the mutilated gear has made one complete revolution the crank axle 16 is returned to its normal position so that the vehicle is restored to its horizontal position and the tongue 17 is engaged by the pawl 25 under the action of the spring 26, whereupon the vehicle is ready for forward movement. It will be obvious that during the backward or reverse movement, owing to the frictional contact of the reversing wheel 14 with the floor surface, the direction of the vehicle is automatically changed so that when next it moves forward it will avoid the obstruction in its path.

40 45 50 55 I claim:

1. Operating mechanism of vehicular toys, which comprises a movable body, a spring motor provided therein, one of the rear wheels of the vehicle being rotated for forward movement by said motor, a normally inoperative reversing

wheel, the other rear wheel being mounted freely upon a crank shaft separated from said first-named rear wheel, a bumper provided in front of said movable body and a transmission mechanism connected with said bumper and adapted for liberating the above crank shaft, the wheel on the crank shaft being lifted from a floor through the transmission mechanism when the movable body strikes against an obstacle so that 10 the reversing wheel is brought into contact with the floor.

2. Operating mechanism of vehicular toys, which comprises a body having a bottom plate, a spring motor mounted on a frame secured to 15 said bottom plate, one of the rear wheels being rotated for forward-movement by said motor, the other rear wheel being mounted freely on a crank shaft separated from the first-named wheel, a toothed wheel rotated reversely by said 20 spring motor and normally inoperative, a pinion projecting beyond the frame and fixed to the axis of said reversing wheel, a mutilated gear disposed opposite to said pinion and fixed on said crank shaft and also having a laterally extending 25 tongue, a bumper projecting from the front end

of the body, a slidable plate associated with said bumper, an operating member engaged with said slidable plate at one end and provided with a pawl normally in engagement with the tongue of the mutilated gear, and a spring for maintaining 5 the tongue and pawl in engagement by pulling the slidable plate and operating member.

3. A vehicular toy comprising a body having front and rear wheels, a spring motor geared to one of the rear wheels for driving the vehicle 10 forward, a crank shaft mounted for rotation in said body the other rear wheel being mounted for rotation on said crank shaft, a normally inoperative reversing gear, a gear secured to said crank shaft and adapted to rotate the same 15 thereby to lower the body at one side, means normally holding said gear against rotation, means operable by contact with an obstacle in the path of the vehicle to release said holding means, and means operable upon lowering of the body to 20 contact with the surface over which the vehicle is traveling and effective to place the crank shaft gear in mesh with the reversing gear.

MASAKICHI FUJII. 25
